UNITED STATES PATENT OFFICE

JOHN J. RITTER, OF URBANA, OHIO, ASSIGNOR TO THE W. B. MARVIN MANUFACTURING COMPANY, OF URBANA, OHIO, A CORPORATION OF OHIO

WINDOW SCREEN

Application filed January 28, 1929. Serial No. 335,542.

This invention relates to improvements in window screens, it more particularly relating to improvements in the frame construction of screens of the extensible, sliding section type.

5 An object of the invention is to provide a screen of improved frame construction whereby contact with the window sill and sash is uniform and continuous throughout its extended length, for the better exclusion of insects and the like.

10 A further object of the invention is to provide interengaging parts between the sections of the screen such that a good sliding connection is secured and the proper relation main-

15 tained.

In the accompanying drawings:

Fig. 1 is an elevation of the rear side of a screen embodying the improvements, the screen in this case being formed of two frames 20 telescoping one with the other.

Fig. 2 is a fragmentary top plan view of the same, enlarged.

Fig. 3 is a partial enlarged front elevation, the broken ends being shown in perspective.

25 Fig. 4 is an enlarged vertical section on the line 4—4 of Fig. 3 with a portion of a window sash shown in place.

Fig. 5 is an enlarged vertical section showing the improved screen in place between the 30 sash and sill of a window.

Referring to the drawing, each section of the screen is formed of a frame, one indicated at A and the other at B, of sheet metal. Each frame is formed with two longitudinal top 35 and bottom strips 1 and 2 connected by vertical strips 3 and 4, the strips being connected by spot-welding or any other suitable manner to form rectangular shaped frames in which the wire mesh 5 is stretched and secured. The 40 wire mesh screen may be secured to the frames by tongues 6 and tabs 7 in the manner shown and described in my pending application Serial No. 260,997, filed March 12th, 1928.

45 Heretofore with screens of this type, considerable space has been left between the sash and sill and one of the sections, owing to the fact that the sash and sill made contact on that section which was off-set by reason of the telescoping construction. To obviate this 50 disadvantage and to enable the window and

sill to make full contact with each of the sections, the construction now to be further described has been devised.

Referring now to Fig. 4, it will be noticed that strip 1, which may be either the top or bottom horizontal frame member of section A, has its outer edge bent to form a horizontal flange 1^a, at substantially right angles to the vertical leg. The horizontal flange 1^a continues as 1^b, and, is bent upwardly, having a slight angular deviation from the portion 1^a and terminates in a downwardly bent flange 1^c substantially parallel to the main vertical strip 1.

The horizontal top and bottom frame strips 2 of section B are also bent in a peculiar manner to form complementary members which interengage with the parts of frame member A. As viewed in Fig. 4 the outer edge of the frame strip 2 is bent at an acute angle to the plane of the strip 2, as indicated at 2^a, then turns upwardly forming a vertical flange 2^b substantially parallel to the strip 2, and it will be noticed that the juncture between the strip 2 and angular portion 2^a is rounded, as indicated at 8. The screen sections A and B when telescoped make contact one with the other at the rounded point 8, lateral displacement being limited by the contact of the lower edges of the flanges 2^b with the sloping part 2^a of strip 2, and also by the fact that these flanges 2^b are confined by the flanges 1^b of the strips 2.

It will be noticed, also, that the edges 9 of the bends between the flanges 1^b and 1^c are slightly outside of the upper edges 2^c of the flanges 2^b and that therefore in the assembled screen the distance between the edges 9 at the top and bottom of the frame section A is greater than the distance between the edges 2^c in section B, so that in closing the window on the screen, contact is first made with the edges 9; with greater pressure these edges are forced inwardly towards one another, until the edges 2^c are met by the window and sill, whereupon full contact with all edges 9 and 2^c of the screen with sash and sill is made.

Having thus described my invention, I claim:

1. In a screen structure, a pair of frame

- members formed of sheet metal strips, the outer edges of the top and bottom strips of one frame member being bent to form lateral channels each of which has a sloping inner wall and an outer vertical wall, the outer edge of which wall forms a contact point, the outer edges of the top and bottom strips of the other frame members being bent to form laterally-extending portions each of which has an in-turned outer edge adapted to be received in the corresponding channel of the other frame member to prevent lateral displacement, said laterally-extending portion being also inclined outwardly to provide a contact point at its outer edge which co-acts with the contact point on the vertical wall of the corresponding channel, said laterally-extending portion being adapted to spring inwardly under pressure of the window and sill to bring said contact points in horizontal alignment with each other, the sliding contacts between said frame members being between the inner surfaces of said laterally-extending portions of one frame member and the junctures between the channels and the strips of the other frame member, said juncture points being rounded.
2. In a screen structure, a pair of frame members formed of sheet metal strips, the outer edges of the top and bottom strips of one frame member being bent to form lateral channels each of which has a vertical outer wall, the outer edge of which forms a contact point for the window and sill, the outer edges of the top and bottom strips of the other member being each bent to form a laterally-extending outwardly inclined portion, the outer edge of which is inturned to be received in the corresponding channel of the other member, the sliding contact between the members being on an intermediate portion of the under surface of each laterally-extending portion and the points where the channels begin, the outer edges of said laterally-extending portions forming contacts with the window and sill and adapted when under the pressure of the window and sill to be pressed in line with the contact points of the vertical walls of the channel.
3. In testimony whereof, I have hereunto set my hand this second day of January, 1929.
- JOHN J. RITTER.
